[57] **CLAIM**

The ornamental design for a transponder support housing, as shown and described.

DESCRIPTION

FIG. 1 is a side perspective view of the transponder support housing, showing my new design with suction cup members shown in phantom and forming no part of the design hereof; FIG. 2 is a side sectional view illustrating details not viewable in a side view; top view thereof, it being understood that the bottom and side views are identical thereto; FIG. 3 is a left side view, a right side view being symmetrical to the left side view; FIG. 4 is a top view; FIG. 5 is a bottom view; FIG. 6 is a rear view; and, FIG. 7 is a front view.
